(57) **CLAIM**

The ornamental design for the tire for automobile, as shown.

DESCRIPTION

FIG. 1 is a perspective view of a tire for automobile in accordance with the new design;

FIG. 2 is a front view thereof;

FIG. 3 is a backside view thereof;

FIG. 4 is a left side view thereof;

FIG. 5 is a right side view thereof;

FIG. 6 is a plan view thereof; and,

FIG. 7 is a bottom view thereof.

The broken line showing of a tire sidewall depicts environment and forms no part of the claim; the dash/dot/dot/dash broken lines depict boundaries of the claim.
